UNITED STATES PATENT OFFICE

HUGH A. SOUTHERN, INCOMPETENT, OF LOS ANGELES, CALIFORNIA, BY GLADYS R. SOUTHERN, GUARDIAN, OF INGLEWOOD, CALIFORNIA, ASSIGNOR TO MERGENTHALER LINOTYPE COMPANY, A CORPORATION OF NEW YORK

TYPOGRAPHICAL COMPOSING MACHINE

Application filed October 16, 1929. Serial No. 399,956.

This invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter elevated and returned through distributing mechanism to the magazine from which they started. More particularly, it relates to machines equipped with a plurality of magazines containing different matrix fonts, and any selected one of which may be brought into action at will.

In one class of such machines, the magazines are arranged one above the other in superposed relation and mounted on separate base frames, the latter conjunctively constituting a so-called "shift-frame" which is movable upwardly and downwardly in the machine to bring one or another of the magazines into operative relation to the assembling and distributing devices. It is also customary to hinge the base frames at their upper ends so that they may be separated or swung apart, when desired, for the purpose of facilitating the independent removal of the magazines and the substitution of others therefor.

The present invention contemplates certain improvements in the mechanism employed for separating the base frames whereby one or more of the magazines may be swung about their pivotal axes for interchange without disturbing others of the superposed series. In the preferred embodiment illustrated, the improved mechanism comprises a manually operable toggle device arranged between the top and bottom magazine base frames, and an open link or hook which is movable to active and inactive positions for making and breaking an operative connection between the uppermost base frame and the one immediately below. Means are

also provided for controlling the movements of the link automatically so that it will or will not function according to the relative position of the magazine shift-frame and the assembling and distributing devices. The specific construction, as well as the features and advantages of the improved mechanism, will best be understood from the detailed description to follow.

In the accompanying drawings, the invention has been shown merely in preferred form and by way of example but obviously many changes and variations may be made therein and in its mode of application which will still be comprised within its spirit. It should therefore be understood that the invention is not limited to any specific form or embodiment except insofar as such limitations are specified in the claims.

Referring to the drawings:

Figs. 1, 2, and 3 are all side elevations of a portion of a linotype machine equipped with the present improvements, and showing the manner of separating the magazines for interchange in different positions of the shift-frame.

The matrices X are stored according to font in the superposed channeled magazines A, three of which are shown herein but of which a greater number might be employed, if desired. The several magazines are mounted on separate base frames A¹, A², A³, conjointly constituting a "shift-frame" which is arranged to be moved upwardly and downwardly in the fixed machine frame to bring any selected one of the magazines into operative relation to a channeled assembler entrance B and a channeled magazine entrance C, the latter leading from a distributor D. The respective magazines are provided with matrix releasing escapements E which, when a magazine is brought into operative position, are actuated through the medium of pivoted levers E¹ by reeds E² controlled from the usual keyboard mechanism. The magazine shift-frame is carried by a sliding plunger E attached to the bottom base frame A³ and which is raised and lowered within a sleeve O by a screw-threaded mechanism L.

actuated by a hand wheel (not shown) through a connecting shaft L².

Each of the magazine base frames A¹ and A² is provided at its rear end and at opposite sides with pivot pins A⁴ which engage in open notches or recesses A⁵ formed in the rear edges of a pair of upstanding plates A⁶ attached to and rising from the relatively fixed lowermost base frame A³. At their forward ends, the base frames A¹ and A² are also each provided at opposite sides with depending blocks A⁷ which rest directly upon the next underlying magazine and serve to maintain the base frames properly spaced apart. However, in order that the magazine selected for use may register accurately with the assembler throat B and the magazine entrance C, two pairs of gage bars F are provided which are arranged near the opposite ends of the magazines at opposite sides thereof, the bars of each pair being connected together by a fore-and-aft piece F¹. These gage bars are supported at their lower ends upon aligning blocks F², attached to fixed side plates O², O³ of the machine frame, and present their upper ends in position to engage the undersides of aligning lugs a projecting laterally from the opposite sides of each base frame at both ends.

The foregoing parts are so arranged and operated that, when any selected magazine is brought into operative position, the aligning lugs a of the corresponding base frame will be caused to bank upon the top of the gage bars F, which thus adjust said base frame facewise relatively to the other base frames and locate the magazine thereon in proper transverse registration with the assembler throat B and the entrance C. To provide for the engagement of the gage bars F with the aligning lugs a, the former are arranged to slide forwardly and rearwardly on the aligning blocks F² so as, in one position, to stand clear of the aligning lugs during the shifting of the magazines and, in the other position, to stand beneath the lugs on the base frame of the selected magazine to allow said frame to bank thereon. It will be noted that the gage bars F are formed in their rear edges with notches f which allow them to clear the aligning lugs a of the lower base frames when the top magazine is brought into use. These notches are made considerably wider than the aligning lugs so as not to interfere with the slight lowering of the shift-frame when banking the operative magazine on the gage bars.

The sliding of the gage bars F is effected by means of a hand lever F³ secured to a rock shaft F⁴ and which extends forwardly therefrom within convenient reach of the operator, an operative connection between the bars and the handle being established by a pair of upright arms F⁵ also secured to said shaft and having their free ends arranged behind and

in engagement with pins f¹ projecting inwardly from the respective fore-and-aft pieces F¹. Pull springs F⁶, anchored to the machine frame, are also employed for holding the bars resiliently in their active position. According to this arrangement, by depressing the hand lever F³, the bars will be drawn forwardly clear of the aligning lugs a and, when the hand lever is released, the springs F⁶ will restore the parts to their normal position. Preparatory to the depression of the hand lever F³, it is necessary to raise the shift-frame slightly in order to relieve the pressure of the operative magazine upon the gage bars and, after shifting the magazines, the new one selected should be brought to a level slightly above that it will eventually occupy in order to permit the gage bars to be moved freely to active position before the aligning lugs a are caused to bank thereon by lowering the "shift-frame."

So far as described, the parts, their construction, and mode of operation are or may be the same as set forth in the Kennedy Patent No. 1,528,434, and in themselves constitute no part of the present invention.

When it is desired to substitute a different magazine for one of those mounted in the shift-frame, the base frames are swung apart about their pivotal axes A⁴ so as to separate them from each other at the front and thus provide the access required for handling the magazines individually. A separate mechanism, carried by the shift-frame, is employed for thus separating the base frames. This mechanism, which is also clearly shown and described in the Kennedy patent mentioned above, usually comprises a transverse rock shaft G journaled in the lowermost base frame A³ and provided at one end with a hand lever G¹. The shaft G is connected to the top base frame A¹ by means of toggle devices arranged adjacent the shift-frame on opposite sides thereof and consisting of a pair of crank arms G², secured to the shaft G, and connecting toggle links G³ pivoted to the base frame A¹. In the Kennedy patent, however, the uppermost base frame is also connected to the lower base frames by slotted links or lost motion devices which establish a permanent connection between all the base frames, such that it is necessary to separate all of the magazines whenever any selected one is to be removed, whether it be the lowermost magazine, a middle one, or the top one. Moreover, it has been found in practice that this particular magazine separating mechanism will not function properly on the type of machine disclosed until certain irrelevant operations have first been performed. For example, if it were desired to remove the top magazine when that particular one is in operative position as shown in Fig. 1, it would be necessary first to relieve the pressure on the gage bars F in the manner before stated, then withdraw the

latter to clear the aligning lugs *a*, and thereafter raise the shift-frame high enough to locate the lugs out of registry with the notches *f*, the last operation being performed so that the bars will be maintained in opposition to the springs *F*⁶ in their inactive position by the aligning lugs of the lowermost base frame, which is usually undisturbed during the separating operation. Otherwise, (that is, without these preliminary operations), the lugs *a* of the second base frame, which as will be observed normally lie partially within one pair of recesses *f*, would engage the upper walls of said recesses during the initial movement of the hand lever *G*¹ and thus prevent further operation of the separating mechanism. Moreover, after the substitution of the new magazine has been effected and the base frames restored by the hand lever *G*¹ to their normal closed condition, the shift-frame must be lowered again to locate the substituted magazine in operative position and allow the aligning lugs *a* of the uppermost base frame *A*¹ to bank upon the gage bars *F*, the latter, in the meantime, having snapped back to their original position as the lugs *a* of the lower base frames moved into registry with the notches *f*. While the Kennedy mechanism would permit the separation of the base frames in the manner required merely by operating the hand lever *G*¹ when the second magazine is in operative position, it should be understood that the top magazine is the one more commonly used and more frequently "changed," and hence the repeated delays and annoyance caused by the extra operations involved in changing this particular magazine are quite objectionable.

The present invention is intended to overcome the foregoing and other difficulties and aims to permit the instant and ready removal and replacement of the uppermost magazine. To this end, the operating handle *G*¹, which, as before stated, is connected directly to the uppermost base frame *A*¹ through the toggle links *G*² and *G*³, is normally (i. e. when the top magazine is in use) disconnected from the other or lower base frames *A*² and *A*³, so that when operated it will act only to swing the top base frame *A*¹ upwardly from its operative position, leaving the other base frames and their magazines undisturbed. Since however it becomes necessary at times to remove the lower magazines as well, provision is made for the operative connection of the operating handle *G*¹ with the middle base frame *A*² so that all the magazines may be separated from each other simultaneously, as in the Kennedy patent. In the present instance, there is employed for this purpose a depending link or hook *H* pivoted loosely at its upper end to one side of the top base frame *A*¹ and formed with an elongated slot *H*¹ which

opens at the top through the forward edge of the link. The link *H* is so arranged that it may be moved about its pivotal axis into and out of operative relation to a stud *a*¹ protruding from one side of the middle base frame *A*². In one position of the link, the stud *a*¹ is adapted to register with the slot *H*¹ at its open end so as to engage therein as the base frame *A*¹ is raised by the hand lever *G*¹; and, in another position of the link, the stud stands clear of the slot to avoid such engagement. When the second magazine is in use, the link *H* will occupy the former position as indicated by the dotted lines in Fig. 1, where it will be caused to engage the stud *a*¹ and lift the middle base frame *A*² as the top base frame *A*¹ is swung upwardly by the operation of the hand lever *G*¹; whereas, when the top magazine is in use, the link will occupy the latter position, as indicated by the full lines in Fig. 1, and thus fail to make connection between the two base frames *A*¹ and *A*², so that when the hand lever *G*¹ is operated, the top base frame *A*¹ may be swung about its pivot independently.

The movements of the link *H* to its active and inactive positions might readily be effected by hand and the link caused to maintain these positions by suitable friction or other means but, in carrying out the invention, it is proposed to control the movements of the link automatically. In the embodiment illustrated, this is accomplished by means of an anti-friction roller *H*² journaled in a fixed horizontal bracket *H*³ on the main frame and adapted to engage the link as the shift-frame is raised and lowered; the lower end of the link *H* being formed with a forwardly projecting cam portion *h* curved on its under edge to engage the roller and beveled or inclined at the top so as to cooperate with the stud *a*¹. The form and relation of the parts are such that, when the shift-frame is lowered to locate the top magazine in operative position, the link *H* will be cammed rearwardly by the roller *H*² away from the stud *a*¹ so as to break connection with the second base frame *A*² and, when the shift-frame is raised to locate one of the lower magazines in operative position, the link will be allowed to resume its active position against the stud *a*¹ and thereby serve to establish a connection between the first and second base frames. When the top magazine is in use, the link *H* (see Fig. 1) is supported by the roller *H*² in a position from which it will be cammed aside by the stud *a*¹ as the hand lever *G*¹ is operated to lift the magazine for removal. That is to say, the beveled edge of the cam portion *h* of the link will engage the stud *a*¹ as the hand lever is pulled forwardly and, by such engagement, cam the link rearwardly so that it will pass upwardly behind the stud and finally, when

the toggles are straightened out, assume the position shown in Fig. 2, a pin on the upper side of the stud a^1 preventing the link from falling forwardly by gravity out of position. 5 Conversely, as the hand lever G^1 is thrown rearwardly to lower the substituted top magazine into operative position, the link H will be guided by the stud a^1 through the same path but in the opposite direction and allowed to reach its original position against the roller H^2 . In this way, the uppermost 10 base frame A^1 may be swung up and down independently of the other base frames in interchanging the top magazine and this without interference with the gage bars F . 15 On the other hand, however, when the second or lowermost magazine is in use, a connection between the base frames A^1 and A^2 is automatically established by the link H 20 through the cooperation of the roller H^2 , so that by merely operating the hand lever G^1 and without any other attention on the part of the attendant, the several magazines may be simultaneously separated for interchange 25 in the manner required, as shown in Fig. 3, and later returned to their normal position. In this connection, it may be noted that the link H allows a certain amount of lost motion between the top base frame A^1 and the underlying base frame A^2 , due to the elongated character of the slot H^1 , and while this is desirable, it is not absolutely essential and especially when the space between the two base frames is great enough to allow the removal of the second magazine from the base frame A^2 without such separation. 30

For the sake of clearness, only one link H is herein shown and described but in practice it will probably be duplicated on the opposite side of the machine in order to obviate undue strain on the second base frame as the latter is being lifted. In this event, the two links might well be fast to a pivot rod journaled in the uppermost base frame so as to obviate the necessity of duplicating the anti-friction control roller H^2 and its supporting bracket. It should also be understood that the invention may be applied to machines equipped with more than three magazines by merely providing additional links H between the pivoted base frames employed. 45

Having thus described the invention, its construction and mode of operation, what is claimed and desired to secure by Letters Patent of the United States, is as follows:

1. In a typographical machine, the combination of a plurality of magazines, separate base frames whereon the magazines are removably mounted, and mechanism for separating all the base frames from each other at one operation to permit the removal of the magazines, said mechanism including means for limiting its operation to one base frame alone whereby that particular base frame may be moved independently of the other

base frames to shift the corresponding magazine to and from its removing position. 50

2. In a typographical machine, the combination of a plurality of magazines, separate base frames arranged one above another in superposed relation and whereon the magazines are removably mounted, and mechanism for separating all the base frames from each other at one operation to permit the removal of the magazines, said mechanism including means for limiting its operation to the uppermost base frame whereby that particular base frame may be moved independently of the other base frames to shift the top magazine to and from its removing position. 75

3. In a typographical machine, the combination of a plurality of superposed magazines, a shift-frame therefor comprising separate base frames whereon the magazines are removably mounted, means for moving the shift-frame to bring one or another of the magazines into operative position, and mechanism mounted in the shift-frame for separating all the base frames from each other at one operation, said mechanism including means for making and breaking an operative connection between the uppermost base frame and the one immediately below it, whereby said uppermost base frame may be moved independently of the other base frames to shift the corresponding magazine to and from its removing position when desired. 90

4. In a typographical machine, the combination of a plurality of superposed magazines, separate base frames whereon the magazines are removably mounted, and mechanism for separating the base frames from each other to permit the removal of the magazines, said mechanism comprising a hand lever, connections therefrom to the base frames whereby the operation of said lever may effect the separation of all the base frames, and means for breaking the connections of said hand lever with all the base frames except the uppermost one, whereby that particular base frame may be moved independently of the others in order to shift the top magazine to and from its removing position. 105

5. In a typographical machine, the combination of a plurality of magazines, separate base frames whereon the magazines are removably mounted, and mechanism for separating the base frames from each other to permit the removal of the magazines, said mechanism comprising a hand lever connected permanently to one base frame, and a device automatically movable to active and inactive position for connecting and disconnecting said base frame with and from another base frame, whereby the operation of the hand lever may effect the separating movement of one or both of said base frames, as required. 120

6. In a typographical machine, the combination of a plurality of superposed magazines, separate base frames whereon the magazines are removably mounted, and mechanism for separating the base frames from each other to permit the removal of the magazines, said mechanism comprising a hand lever connected permanently to the uppermost base frame, and a device movable to active and inactive position for connecting and disconnecting said base frame with and from an underlying base frame, whereby the operation of the hand lever may effect the separating movement of one or both of said base frames, as required. 75
7. In a typographical machine, the combination of a plurality of superposed magazines, a shift-frame therefor comprising separate base frames whereon the magazines are removably mounted, means for moving the shift-frame to bring one or another of the magazines into operative position, mechanism for separating the base frames from each other to permit the removal of the magazines, said mechanism comprising a hand lever carried by the shift-frame and connected to the uppermost base frame, and means for connecting and disconnecting said base frame with and from a lower base frame automatically as the shift-frame is raised and lowered, whereby the operation of the hand lever may effect the separating movement of one or both of said base frames, as required. 80
8. In a typographical machine, the combination of a plurality of superposed magazines, separate base frames whereon the magazines are removably mounted, and mechanism for separating the base frames from each other to permit the removal of the magazines, said mechanism comprising a hand lever connected to the uppermost base frame, a hook or link depending from said base frame, and means for connecting and disconnecting the link with and from a lower base frame. 85
9. In a typographical machine, the combination of a plurality of superposed magazines, separate pivoted base frames whereon the magazines are removably mounted, and mechanism for separating the base frames from each other to permit the removal of the magazines, said mechanism comprising a hand lever, and means for connecting said lever to the uppermost base frame alone or to a plurality of base frames simultaneously, as desired. 90
10. In a typographical machine, the combination of a plurality of superposed magazines, a shift-frame therefor comprising separate pivoted base frames whereon the magazines are removably mounted, means for moving the shift-frame to bring one or another of the magazines into operative position, mechanism for swinging the base frames apart to permit the removal of the magazines, said mechanism comprising a hand lever mounted in the shift-frame and permanently connected to the uppermost base frame, a depending hook or link carried by said base frame, and means whereby the hook is automatically connected and disconnected with and from the next underlying base frame as the shift-frame is raised and lowered. 100
11. In a typographical machine, the combination of a plurality of superposed magazines, a shift-frame therefor comprising separate pivoted base frames whereon the magazines are removably mounted, means for moving the shift-frame to bring one or another of the magazines into operative position, mechanism for swinging the base frames apart to permit the removal of the magazines, said mechanism comprising a hand lever mounted in the shift-frame and connected to the uppermost base frame, a depending hook or link pivoted to said base frame, and a relatively fixed abutment arranged to engage the link as it is raised and lowered by the movement of the shift-frame and by such engagement connect it with or disconnect it from the second base frame from the top. 105
12. A combination as in claim 7, characterized by the fact that the automatic connection and disconnection of the two said base frames is effected as the top magazine is carried out of and into operative position by the movement of the shift-frame. 110
